UNITED STATES PATENT OFFICE.

MICHEL PERRET, OF LYONS, FRANCE.

FIRE-GRADE.

SPECIFICATION forming part of Letters Patent No. 236,252, dated January 4, 1881.

Application filed August 13, 1880. (No model.) Patented in France July 28, 1877.

To all whom it may concern:

Be it known that I, MICHEL PERRET, manufacturer, a citizen of the Republic of France, and residing in Lyons, France, have invented 5 Improvements in Fire-Grates, (for which I have obtained a French patent, July 28, 1877, No. 119,651,) of which the following is a specification.

This invention relates to a particular disposition of fire-grates which permits the realization of certain conditions very important with respect to a good combustion—conditions which have not heretofore been obtained.

In all industrial furnaces the bars of the fire-grates are separated a distance calculated according to the fuel employed, the volume of air to be admitted in a given time, and, in general, according to the multiple conditions imposed by the particular result which it is desired to obtain; but, however exact the relative proportions may be at the beginning, the normal supply of air intended lasts but a little while, on account of the expansion and clogging of the bars, which change the sections of the air-passages, and also on account of the rapid destruction of the grate. The last objection is specially noticeable in fires provided with forced blasts, and it is perhaps to be attributed to this that this class of fires 30 is received with so small favor, notwithstanding the advantages they afford in many cases. The disposition which I employ has the effect of preventing all warping, of maintaining the metal at a constant temperature, which assures uniformity in the conditions whereon the passage of the air through the limited orifices or air-spaces depends, of facilitating the clearing of the grate, and of assuring its preservation.

The grate that is adopted is composed of a series of bars of sufficient depth to dip into water in such manner as to be constantly kept cool, and consequently protected from rapid destruction. To this end the entire grate is 45 placed in a box, which may be of strong sheet-iron, filled with water to a suitable height. The box is provided with openings for the inflow of the blast, which passes between the water and the grate and then through the openings 50 in the latter. Another orifice serves for feeding the water, so as to maintain it at the proper

level. A suitable opening also permits the ashes which fall into the water in small quantities to be withdrawn. The difference of expansion between the part of the bars which is 55 in immediate contact with the fire and that which is cooled by immersion would naturally produce tensions tending to break the metal. This difficulty is avoided by the shape of the cooling-plates. These are comparatively thin and deep, and decrease in length toward the bottom, where the length is approximately equal to or less than the depth. As a further security, in some cases perpendicular openings or slots are formed in the plates, 60 and then the depth should be equal to or exceed the length between the ends of the plates and the slots, or between the slots where there are two or more. Equal expansion of all the parts is thus secured.

70 Heretofore a grate has been devised in which the bars are provided on the bottom with webs that dip in the water-trough below. These webs are, however, comparatively long, thick, shallow, and are continuous, and each is provided with an independent trough, the draft or air blast passing between the troughs. This part of the present invention differs therefrom in the shape of cooling-plates, in the use of perpendicular openings or slots in such plates, 75 and in the common water-vessel which forms the bath in which a series of cooling-plates dip, so that the blast or draft passes over the surface of said water and between the said plates. The cooling of the grate lowers the 80 temperature of the ashes on its surface, prevents their adherence, and permits the ready removal of them from above when the bars are close together, or from below when they are a sufficient distance apart. In the latter 85 case the delivery is facilitated by a proper tool or by a simple oscillation of the bars.

90 The grate is not necessarily composed of bars. It may be formed of a metallic plate of suitable thickness, pierced with orifices of any 95 suitable form, and provided with ribs on its lower surface of sufficient depth to plunge into the sheet of water placed beneath, and to preserve always the space necessary for the introduction of air between the level of the 100 water and the surface upon which the fuel burns. The cooling due to the partial immer-

sion of the grate, by assuring the permanence of their forms, permits the sections of the air-holes to be exactly determined.

It is possible to reduce the sections as much as may be necessary for the employment of dry and pulverulent fuel; but with openings of substantially uniform section at a certain reduction—two millimeters, for example—the air passes with difficulty, an excess of pressure becomes necessary, and gives rise to partial lifts of the fuel, and consequent inequalities in the passage of the air, and an irregular burning of the fire.

I have devised a simple means whereby the passage of air through openings the most reduced in horizontal section, and of any suitable form, is facilitated. This means consists in the widening or beveling of the upper part of the openings near the fuel, so as to give to the air a more extended surface, and at the same time an oblique direction, which permits all parts of the fuel to be properly reached. The regular passage of the air through thin layers of fuel, with a pressure of only a few 25 centimeters of water, is thus secured. This disposition can be adapted to furnaces which are not provided with a blast, and permits the reduction in cross-section of the air-passages by facilitating the penetration of the air in the 30 layers of the fuel.

Experience has shown that the quantity of water evaporated by the contact of the grate-bars is not important, even in case hot air is used. The water-vapor produced has, in fact, 35 a real utility. By its decomposition it tends to lower the temperature of the fire-bed, which would have a bad effect upon the exposed parts of the heater, and the combustion of the hydrogen restores, at a distance from the fire, 40 the absorbed heat, producing flames even in case of fuels which ordinarily burn without flame, such as pure anthracite.

The immersion of the bars, of which the particular object is to cool them, can be dispensed 45 with by giving them a sufficient depth and thickness. This feature has a special importance for application to locomotive-furnaces. Under these conditions the refrigerating agent would be air. In other cases steam taken 50 from the boiler could be employed, it being blown between or under the bars in such manner as to cool the plates, which are then surrounded by steam, instead of being plunged into water, as above indicated.

55 The possibility of employing hot air without alteration in the grate is very advantageous in furnaces supplied with a blast, since it permits the recovery of heat from the gases of combustion, this heat not being necessary for 60 creating a draft. The recovery of part of the heat can be accomplished by divers means. I have employed metallic tubes presenting a large surface.

In the accompanying drawings, which form 65 a part of this specification, I have represented some of the forms which can be adopted for

realizing the principles of my invention, without, however, intending to confine myself to these forms, which are eminently variable, according to the object and principal purpose of 70 the grate.

On all the figures, A represents the grate-bars, which are, as shown, of considerable depth, so as to form cooling-plates *a*, and which dip into the water-bath B.

75 Figure 1 illustrates, by views in side elevation, plan, and section, the construction of one type of grate-bar. It is provided with a vertical opening or slot, *a'*, in the plate *a*, to enable it to withstand the action of cooling.

80 In Fig. 2 is represented a style of bar with only a small portion of its cooling-plate immersed.

By examining the views in elevation and section on dotted lines in view in elevation, 85 it will be seen that the thickness and depth of the bar or plate will vary with the distance from the cooling-liquid in such manner as to carry off the heat, and thus prevent the excessive heating and rapid destruction of the 90 grate.

85 In Fig. 3, which consists of views in side elevation and central vertical section, the cooling-plate is trapezoidal in form. It can also be made triangular, as shown in dotted lines.

95 Fig. 4 is a plan, and Fig. 5 a section, of a partially-immersed grate formed of bars notched or cut away at the sides, so that when placed together a series of cross or star shaped holes are formed, very small at the bottom, but inclined or flaring at the top, as indicated at *a''*. An oblique direction is thus given to the air, which permits it to reach all parts of the fuel.

105 In Fig. 6, which consists of views in side elevation and section on the dotted line, the cooling-plate is provided with two openings or slots, and is somewhat modified in form from that shown in Fig. 1.

110 My system of grates presents special advantages in connection with fires or furnaces having a forward blast; but the principles enunciated are applicable as well to fires burning by an internal draft.

Having thus explained the said invention 115 and the manner of carrying the same into effect, what I claim, and desire to secure by Letters Patent, is—

1. A fire-grate provided with cooling-plates 120 of the form shown, the same being comparatively thin and decreasing in length toward the bottom, and having a depth approximately equal to or greater than the length at the lower part of the plates between the ends, or between the ends and one or more vertical 125 slots in the plates, substantially as described.

2. A grate-bar having a comparatively thin 130 depending cooling-plate extending longitudinally of said bar, and being of a depth approximately equal to or greater than the length of the plate at the bottom, between its ends, or between the ends and one or more vertical

slots formed in the plate, substantially as described.

3. In a fire-grate, a cooling-plate provided with one or more vertical openings or slots, substantially as described.

4. In a fire-grate, the air-openings inclined or flaring at the upper surface, substantially as described.

5. The combination, with a grate having a series of cooling-plates, of a common water-vessel, into which said series of plates dip, the said vessel substantially filling the space under said grate, and said plates having a sufficient depth to allow the blast or draft to pass

over the surface of the water-bath in the vessel and between the plates, substantially as described.

6. A fire-grate provided with cooling-plates and having contracted air-openings inclined or flaring on the top, substantially as described.

In testimony whereof I have signed my name to this specification in the presence of two subscribing witnesses.

MICHEL PERRET.
